US00D869975S

(12) **United States Design Patent** (10) Patent No.: **US D869,975 S**
(45) Date of Patent: ** *Dec. 17, 2019

(54) **CONTROL PANEL FOR ELEVATOR**

(71) Applicant: **Mitsubishi Electric Corporation**,
Tokyo (JP)

(72) Inventors: **Takanori Hikima**, Tokyo (JP); **Naoki Furuhata**, Tokyo (JP); **Kohei Kurose**, Tokyo (JP)

(73) Assignee: **Mitsubishi Electric Corporation**,
Tokyo (JP)

(*) Notice: This patent is subject to a terminal disclaimer.

(**) Term: **15 Years**

(21) Appl. No.: **29/619,884**

(22) Filed: **Oct. 3, 2017**

(30) **Foreign Application Priority Data**

May 30, 2017 (JP) 2017-011555

(51) **LOC (12) Cl.** **10-05**

(52) **U.S. Cl.**

USPC **D10/108**

(57) **CLAIM**

The ornamental design for a control panel for elevator, as shown and described.

DESCRIPTION

FIG. 1 is a front, top and right side perspective view of a control panel for elevator showing our new design;

FIG. 2 is a front view thereof;

FIG. 3 is a rear view thereof;

FIG. 4 is a top view thereof;

FIG. 5 is a right side view thereof; and,

FIG. 6 is an enlarged partial perspective view of FIG. 1.

1 Claim, 5 Drawing Sheets
